UNITED STATES PATENT OFFICE.

KENNETH J. TOBIN, OF CHICAGO, ILLINOIS, ASSIGNOR OF ONE-THIRD TO ELMER P. RENSTROM AND ONE-THIRD TO WILLIAM G. SALKELD, OF CHICAGO, ILLINOIS.

CLAMP.

1,409,798.

Specification of Letters Patent. Patented Mar. 14, 1922.

Application filed October 7, 1921. Serial No. 505,984.

To all whom it may concern:

Be it known that I, KENNETH J. TOBIN, a citizen of the United States, residing at Chicago, in the county of Cook and State 5 of Illinois, have invented certain new and useful Improvements in Clamps, of which the following is a full, clear, and exact specification.

This invention relates to rope or cord 10 clamps and is directed to improvements in clamps employing a pivoted tension member and intended for use with the smaller sizes of ropes such as clothes lines although not limited thereto.

15 The objects of the invention are to provide a clamp of simple and economical construction in which the rope or cord will be held by its own tension in such a manner that slippage is impossible and without risk 20 of cutting the rope when the tension on it is high, while also preventing release of the rope should it become slack.

These objects are attained by the novel 25 combination of elements here disclosed by which is produced a clamp consisting of a pivoted tension lever and base plate provided with means, such as a stop on the clamping arm of the lever, preventing absolute contact of the arm with the plate in 30 order to avoid possibility of cutting the rope being held, and also with means, such as lugs on the base plate on each side of the clamping arm, for retaining the end of the rope beneath the arm when the clamping 35 tension is removed and for forming a restricted space in conjunction with said stop and arm into which the rope is wedged when clamped.

These and other minor objects are attained by the construction and arrangement 40 of parts, or equivalents thereof, set forth in the following specification and claimed.

Referring to the drawings;

Fig. 1 is a perspective view of the clamp 45 holding a rope end.

Fig. 2 is a plan view of the clamp showing an intermediate part of a rope engaged therein.

Fig. 3 is a plan view of the base plate.

50 Fig. 4 is a side view of the tension lever, and

Fig. 5 is a longitudinal sectional view showing the tension lever in position on the base plate.

55 The clamp embodying my invention com-

prises a base plate 10 formed with a central slot 11 extending into the plate from its upper edge and with pivot ears 12 on each side of the slot and near the upper edge of the plate. A tension member or lever 13 is 60 pivoted between its ends on the ears 12 by means of lateral studs or trunnions 14 which are received in bearing recesses formed by under-cutting the pivot ears. This construction of plate and lever permits the two 65 to be readily assembled but prevents removal of the tension lever after the plate has been mounted on a support.

The tension member 13 has oppositely projecting aligned arms one of which constitutes 70 a tension arm projecting substantially its whole length beyond the plate and being hooked or curved in a vertical plane so that its lower edge is arched or concaved through its length, as at 15, to receive and retain a 75 rope. The other or clamping arm of the member or lever 13 extends over the plate and is formed with a thickened portion or projection 16 positioned to come in contact with the plate 10 at the base of the slot 11 80 and with a substantially straight clamping edge 17 spaced above the contacting edge of projection 16 a distance substantially half the thickness of the rope with which the clamp is designed to work. The end of the 85 clamping arm is beveled or upturned as at 18 to facilitate insertion of the rope. In order to prevent dropping of the rope end from beneath the clamping arm, lugs 19 are formed on plate 10 on each side of the clamping 90 arm and adjacent thereto. These lugs are inclined or rounded at the top to cooperate with the beveled end 18 of the clamping arm in directing the rope beneath the clamping edge of the arm and spaced from projection 16 substantially the same distance as the clamping edge is above the plate, that is, a distance about equal to half the diameter or thickness of the rope to be held and have straight inner edges 20 so that a square 95 walled space of less area than the diameter of the rope is left between the projection 16, lugs 19, and the clamping arm and plate when the clamp is closed, and in this space the rope is securely wedged without danger 100 of being cut.

When using the clamp to hold the end of a rope, the end is passed above the lugs 19 and beneath the clamping arm then around under the tension arm where it engages in 110

and is retained in the concaved edge 15, as shown in Fig. 1. When the mid portion of the rope is to be held, it is looped and the loop passed under the clamping arm, the 5 crossing of the loop being under the tension arm, as shown in Fig. 2. In both cases the tension given the rope causes the clamping arm of the lever to crowd or wedge the rope in the space between projection 16 and 10 the edges 20 of the lugs where it is securely held as long as the rope is under tension. Should the rope be temporarily slackened, the lugs 19 will prevent the end of the rope from falling out from beneath the clamping arm. 15 The rope can not be severed by excessive pressure of the clamping arm as the projection 16 prevents actual contact of the clamping edge with the plate.

I claim as my invention,

- 20 1. A clamp comprising a base plate and a rocking member pivoted near one edge of the plate, said member having opposite arms one of which has its lower edge of arcuate form and constitutes a tension arm, the 25 other with a substantially straight clamping edge presented towards the plate, and means for limiting the movement of said last mentioned arm towards the plate.
2. A clamp comprising a base plate and a 30 rocking member pivoted thereon, said member having opposite arms one of which has its lower edge of arcuate form and constitutes a tension arm, the other being formed with a clamping edge presented towards the 35 plate, a projection on the arm adapted to engage the plate and limit the approach of said arm, and cord retaining lugs formed on the plate adjacent said last mentioned arm and spaced from said projection.

3. A clamp comprising a base, a clamping member pivoted thereon, means for actuating the clamping member by the tension of the engaged rope, and projecting elements on the base and the clamping member co-operating when the clamp is closed to form 45 a restricted space of less diameter than the cord to be held into which the cord is crowded when clamped.

4. A clamp comprising a base plate, a rocking member pivoted thereon and formed 50 with a clamping arm extending over the plate, said arm having a projection near the pivot of the rocking member adapted to engage the plate and limit approach of the arm thereto, a projection on the plate at 55 each side of the clamping arm and spaced from said projection on the arm, the facing edges of said projections on the arm and plate, together with the arm and plate, circumscribing a space when the clamp is closed 60 of less area than the diameter of the cord to be held and into which the cord is wedged when clamped, and means for actuating the clamp by tension of the engaged cord.

5. A clamp comprising a base plate and 65 a rocking member pivoted thereon, said member having a clamping arm extending over the plate, and a cord retaining lug formed on the plate adjacent each side of the clamping arm, the end of said arm and 70 the upper edges of the lugs being oppositely inclined to form a guide for insertion of a cord beneath the arm, and means for actuating the clamp by tension of the engaged cord.

75 In testimony whereof I affix my signature.

KENNETH J. TOBIN.
